(57) CLAIM

The ornamental design for a covered bowl, as shown and described.

DESCRIPTION

FIG. 1 is a front side elevational view of a covered bowl showing my new design, the rear elevational view being identical;

FIG. 2 is a top plan view thereof;

FIG. 3 is a left side elevational view thereof, the right side elevational view being identical; and,

FIG. 4 is bottom plan view thereof.

The surface ornamentation on the surfaces in FIGS. 2 and 4 which are not shown ornamented in FIGS. 1 and 3 is disclaimed.
